CLAIM

The ornamental design for a bearing with integral diverted lantern ring for a rotary mechanical device, as shown and described.

DESCRIPTION

FIG. 1 is a top perspective view of a bearing with integral diverted lantern ring for a rotary mechanical device showing our new design;

FIG. 2 is a bottom perspective view of a bearing with integral diverted lantern ring for a rotary mechanical device showing our new design;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top plan view thereof;

FIG. 8 is a bottom plan view thereof; and,

FIG. 9 is a top perspective view of the two halves of a bearing showing our new design.

1 Claim, 5 Drawing Sheets
